United States Patent

Des. 239,721

Patented Apr. 27, 1976

239,721

PRINTER STATION

Myron F. Davis, Jr., Boca Raton, Fla., and Charles A. Pycha, Rochester, Minn., assignors to International Business Machines Corporation, Armonk, N.Y.

Filed Jan. 10, 1975, Ser. No. 540,308

Term of patent 14 years

Int. Cl. D14—02

U.S. Cl. D26—5 C

FIG. 1

FIG. 2

FIG. 1 is a front perspective view of a printer station showing our new design; and

FIG. 2 is a rear plan view thereof.

The left side of the printer station is identical to the right side shown in FIG. 1, except that the smaller knob near the front in FIG. 1 is not present on the left side.

We claim:

The ornamental design for a printer station, as shown and described.
